A. JOHNSON,
RUBBER FOOTWEAR,
APPLICATION FILED JULY 26, 1915.

1,168,306.

Patented Jan. 18, 1916

UNITED STATES PATENT OFFICE.

ALFRED JOHNSON, OF DULUTH, MINNESOTA.

RUBBER FOOTWEAR.

1,168,306.

Specification of Letters Patent. Patented Jan. 18, 1916.

Application filed July 26, 1915. Serial No. 41,899.

To all whom it may concern:

Be it known that I, ALFRED JOHNSON, a citizen of the United States, residing at Duluth, in the county of St. Louis and State of Minnesota, have invented certain new and useful Improvements in Rubber Footwear, of which the following is a specification, reference being had therein to the accompanying drawing.

10 This invention consists of certain improvements in rubber footwear and relates particularly to the specific form of attaching means for such.

The object is to provide simple, cheap and 15 dependable holdfast means for such wear.

Another object is to provide holdfast means which will render the detachable sole when applied to the shoe as nearly water tight as possible.

20 Referring now to the accompanying drawings forming part of this application and in which like numeral characters indicate like parts: Figure 1 is a side elevation of a shoe equipped with my improved device.

25 Fig. 2 is a transverse vertical section through the center of the shoe thus equipped. Fig. 3 is a top plan view of a detachable sole equipped with my improved holdfast means. Fig. 4 is a perspective view of one 30 end of the holdfast means with the rubber removed therefrom, and Fig. 5 is a vertical section of a portion of the holdfast means taken on the line A—B, Fig. 4.

1 represents the vamp of a shoe with the 35 ordinary sole 2 attached and to which my improved detachable rubber sole is applied. The latter consists of the usual heavy wearing base 3 and the continuous flexible side wall 4. Within the side walls 4 adjacent the 40 innermost edge and extending the entire length thereof is incorporated in any suitable manner a spring wire 5. This wire is so formed previous to being placed within the side walls as to normally exert an inward tendency of the side walls of the sole, to cause the same to snugly fit against the 45 vamp of the shoe when applied thereto. The ends of the wire 5 which terminate at the instep-end of the sole are each formed 50 into a gripping member, practically identical in construction, with the exceptions hereinafter noted. As is evident, these soles are made in pairs, each having an inner and outer side. The outer gripping mem-

ber upon the corner 6 is formed by the wire 55 5 being bent at right angles inwardly a short distance from the instep end of the sole, then turned again at right angles and extending parallel with the body thereof, until approximately within the edge of the 60 inner end of the sole, then it is turned again at right angles and extends outwardly approximately twice the distance it was bent in the opposite direction, then bent at right angles downwardly a distance slightly less 65 than the thickness of an ordinary shoe sole, then at right angles inwardly, forming a portion 7 equal in length to the portion 8, then bent at right angles longitudinally the sole forming the portion 10, then bent at 70 right angles to extend outwardly, forming the portion 11, equal to the portion 7 and parallel therewith, then bent at right angles upwardly, forming the portion 12, equal to the portion 13 and parallel therewith, then 75 bent at right angles inwardly and securely fixed in any substantial manner such as with solder or the like at the point of first bending. Thus we have formed a sole gripping device inclosed upon three sides and designed to snugly engage the sole of a shoe when applied thereto, the portion 10' being slightly depressed for such purpose. The wire forming the portions 12 and 13 is flattened in a direction transverse the sole 80 and such flattened portion extends somewhat upon the extensions of the wire forming such portion and the inside edges of said flattened portions are made sharp as at 85 14, Fig. 5. These sharpened portions are 90 for the purpose of more secure engagement with the edges of the sole 2, when applied thereto, and will become slightly embedded or indented within the edges of the sole when in place.

95 To the upper portion of the gripping means above described is securely attached in any desired manner an upwardly and outwardly extending loop of wire 16. This loop may either be fastened by soldering, 100 or if preferred, formed of the same piece of wire as that of the gripping means. This loop 16 is for the purpose of providing a convenient thumb piece for the application of the device and is designed to be entirely 105 covered by the material forming the removable sole. The portion 10 is also intended to be entirely surrounded by the material

2
forming the sole and only the portion 10' and the inside edges of the portions 12 and 13 are designed to engage the sole of the shoe direct.

- 5 The gripping member upon the opposite corner 17 of the removable sole is formed integral with the opposite end of the wire 5 and in form is identical with the outside holdfast means just described, except that 10 the outer vertical portions thereof, are not flattened nor sharpened in any manner whatever and there is no loop to correspond with the loop 16 upon the outer holdfast means, as it has been demonstrated in practice that such is unnecessary. The inner gripping means is preferably entirely embedded within the material forming the sole, with the exception of the portion 18 which is formed slightly depressed like the portion 20 10' on the opposite gripping means.

Across the instep-end of the removable sole is formed a relatively narrow strip 19 of comparatively soft material, such as rubber or the like which will form as nearly as 25 possible, a water tight joint when applied to a shoe.

From the foregoing, the application and operation of the device will be readily understood.

- 30 In applying the over-sole to a shoe, it is preferably drawn on over the sole thereof endwise, the inside gripping means slipped into place over the inside of the instep portion of the shoe sole, then by forcibly pinching with an outward rolling motion upon the member 16 of the outermost gripping means, the latter will be readily opened to snap over the outer edge of the instep portion of the shoe sole, which will complete 35 40 the application of the removable sole to the shoe, and the natural inward draft upon the oppositely disposed gripping members, will cause the sharpened edges of the portions 12 and 13 of the outside member to become 45 slightly embedded within the outermost edges of the shoe sole, and thus effectually

prevent the outside of the oversole from creeping, which otherwise it would be inclined to do.

Having thus described my invention, what 50 I claim as new and desire to secure by Letters Patent is—

1. An article of footwear, comprising a removable sole, an engaging portion extending upwardly and inwardly from the edges 55 of the sole, and a spring wire incorporated within the engaging portion throughout its entire length and terminating at both ends in a gripping means whereby the article is securely held in position when placed upon a 60 shoe.

2. A removable article of footwear, comprising a sole, and engaging means partly surrounding the sole and terminating in resilient gripping means at the corners of the 65 instep end of the sole.

3. A removable sole of the character described having a spring wire incorporated within the uppermost shoe engaging edges thereof, one end of said wire terminating in 70 a gripping member, and the opposite end terminating in a gripping and cutting member.

4. A removable sole of the character described, having a spring wire incorporated 75 within the uppermost shoe engaging edges thereof, both ends of said wire terminating in resilient gripping members.

5. A removable sole of the character described having a spring wire incorporated 80 within the uppermost shoe engaging edges thereof, and a resilient gripping member formed integral with each end of the spring wire, the outside one of said members having an upwardly and outwardly extending 85 portion by which it is manipulated.

In testimony whereof I hereunto affix my signature in the presence of two witnesses.

ALFRED JOHNSON.
